OP D 13,015

DESIGN FOR A DESK-FRAME.

Design No. 13,015, dated June 27, 1882.

UNITED STATES PATENT OFFICE.

CHARLES PAGE, OF PHILADELPHIA, PENNSYLVANIA.

DESIGN FOR A DESK-FRAME.

SPECIFICATION forming part of Design No. 13,015, dated June 27, 1882.

Application filed March 28, 1882. Term of patent 7 years.

To all whom it may concern:

Be it known that I, CHARLES PAGE, a citizen of the United States, residing in the city and county of Philadelphia, State of Pennsylvania, have invented and produced a new and original Design for Desk-Frames, of which the following is a specification, reference being had to the accompanying photographic illustration, forming part thereof.

10 A represents the side piece of the frame of the desk, and B the seat-support thereof.

In the piece A are panels a with leaves b, a trefoil, c, with leaves d radiating therefrom, two connected scrolls, e, with a scroll, f, in the 15 space below said scrolls e, an edge scroll, g, uniting the front edge, g', of the frame A with the leg g'' thereof, a panel, h, with a diagonal bar, k, and a spirally-fluted arch, m, uniting the legs g'' g'''. The sides of the panel h are 20 the legs g'' g'''. The top and bottom of said panel h are the scroll g and arch m, respectively. The seat-support B is of tapering form with scrolls n on its side.

I claim—

1. The design for desk-frame, having the 25 panels a with leaves b, substantially as set forth.
2. The design for desk-frame, having a trefoil, c, with leaves d, substantially as set forth.
3. The design for desk-frame, having two 30 connected scrolls, e, with a scroll, f, below the same, substantially as set forth.
4. The design for desk-frame, having the frame h with a diagonal bar, k, substantially as set forth.
5. The design for desk-frame, having the 35 spirally-fluted arch, substantially as set forth.
6. The design for desk-frame, having the panel h, formed of the scroll g at top, arch m at bottom, and legs g'' g''' at the sides, substantially as set forth.

CHARLES PAGE.
